UNITED STATES PATENT OFFICE.

HARVEY DIKEMAN, OF DANBURY, CONNECTICUT, ASSIGNOR OF SEVEN-TWENTIETHS
TO WILLIAM H. FOLEY, OF DANBURY, CONNECTICUT.

MILK-BOTTLE.

1,083,201.

Specification of Letters Patent.

Patented Dec. 30, 1913.

Application filed June 5, 1913. Serial No. 771,981.

To all whom it may concern:

Be it known that I, HARVEY DIKEMAN, citizen of the United States, residing at Danbury, in the county of Fairfield and State of Connecticut, have invented certain new and useful Improvements in Milk-Bottles, of which the following is a specification.

My invention relates to bottles, such as are adapted to contain milk, cream, and other liquids, liable to contamination, and particularly to that form of bottle wherein a flat paste-board cap is used for the purpose of closing the mouth of the bottle. In restaurants, delivery wagons, and freight cars, bottles of milk and cream are packed in cases, and to keep the milk, cracked ice or large ice cakes are placed over the tops of the cases. There is a considerable quantity of dirt in ice, especially where it is used in this manner and is unprotected from dust, and when the bottle of milk is brought into the home or where the bottle is served in a restaurant, the face of the cap is very liable to have on it water, or other liquid, and more or less dirt, black specks, and other residue from the melted ice. The upper face of the paste-board bottle-cap therefore forms a dirt collector, and the cap forms a cup which will retain such dirt. The danger comes in removing these caps. The cap cannot be lifted straight up whether it is pried out or is lifted by a tab. One edge must come up first. The cap in the ordinary milk bottle is inserted within a circular rim which extends entirely around the cap and which is slightly smaller than the diameter of the cap, and hence the cap is bound tightly in this rim, and when the cap is lifted up one edge comes up first, and the cap is accordingly tipped transversely across the mouth of the bottle so that dirt, dirty water, foreign matter, etc., runs off the edge of the cap and into the milk, thus contaminating the latter. This milk may be poured from the bottle into a jug and kept for future use, and in this case, the germs which may be in the milk, will of course, thrive, and render the milk still more contaminated. If the cap is cleaned, prior to being lifted from the bottle, no particular damage, will occur, but this cleaning of the cap is very rarely done, and almost invariably the result is that no matter how clean the milk may have been in the first instance, or how

uncontaminated, in the operation of lifting it the cap from the bottle there is dumped into the milk not only dirty water from melted ice, but a number of dirt particles and germs. As before stated, the mouth of the bottle is formed with an annular seat or recess within which the cap fits and even if the particles of dirt upon the cap are deposited upon this seat by the lifting up and tilting of the cap, when the milk is poured out the milk will come in contact with this dirt and thereby become contaminated.

The primary object of my invention is the provision of a milk bottle whose mouth is so formed as to permit the use of the ordinary circular card-board cap, but which will prevent the tilting of this cap and the contamination of the milk in the manner before described.

A further object of the invention is to form the mouth of the bottle that the margin of the cap will project on each side beyond the mouth of the bottle so as to overhang, as it were, the rim of the mouth, so that no dirt can possibly find its way into the mouth and in this connection to so form the mouth of the bottle that dust and particles of foreign matter are liable to slip off the rounded exterior face of the mouth.

A further object of the invention is to provide a milk bottle of the character above described, so constructed as to permit the cap to be more readily detached without the necessity of either inserting an instrument into the mouth of the bottle to pry up the cap or without the necessity of providing the cap with a tab.

Other objects will appear in the course of the following description:

My invention is illustrated in the accompanying drawings, wherein:

Figure 1 is a perspective view of the upper portion of a milk bottle constructed in accordance with my invention, the cap being shown spaced therefrom. Fig. 2 is an enlarged vertical section showing the cap in place.

Corresponding and like parts are referred to in the following description and indicated in all the views of the accompanying drawing by the same reference characters.

Referring to these figures, 2 designates the milk bottle of the usual or ordinary shape, the upper end of which is formed with a downwardly rounded annular rim 3. As

will be seen in Fig. 2, this rim forms a thickened portion at the mouth of the bottle and the upper face of the rim is flattened as at 4 so as to form a flat annular seat for the cap. This flat annular seat is surrounded by a downwardly extending rounded face 5. Disposed at equi-distant points around the rim 3 are the upwardly projecting ears or lugs 6, the inner face of which intersect the downwardly extending rounded face 5 of the rim outward of the outer circumference of the seat 4. These lugs 6 may be slightly undercut upon the inner faces so as to overhang the face 5 and provide for a more complete and firm engagement with the stopper. This stopper has the form ordinarily used with milk bottles today, that is, it is made of a circular disk of cardboard, and is designated 7. The diameter of this stopper 7 is very slightly greater than the circle partially defined by the inner faces of the lug 6 so that when the stopper is forced down upon the bottle its circumference will firmly engage the inner face of the lug 6 and the stopper will be firmly held in place tightly upon the seat 4, the stopper disk extending beyond the disk 4, entirely around the bottle. Under these circumstances, if dust or particles of dust do collect upon the upper face of the disk, and the bottle be inclined the dirt will not be caught by the upwardly extending annular flange of the bottle mouth, as would be the case in the present construction of bottles, but simply slips off and over the rounded face 5 of the rim 3. Furthermore, as the disk 7 projects beyond the seat 4, it is impossible for dirt particles to work their way around the edges of the cap and into the bottle. Again, when raising the cap, the cap is tilted in the usual manner, but this tilting action does not necessitate the cap being tilted so as to discharge the particles upon the upper face of the cap into the bottle or onto the seat 4, but the cap is simply raised up at one side and whatever particles may be upon the cap, or any liquid which may be upon the face of the cap is slid off over the rounded face 5 of the rim 3. Furthermore, a bottle constructed in accord-

ance with my invention permits the cap to be readily raised from its engagement with the bottle by simply taking hold of the edge of the disk and raising it up, the rounded face 5, in conjunction with the projecting margin of the cap, permitting the cap to be easily taken hold of by the fingers or pried up by a fork.

It will be seen that my bottle may be constructed as readily and cheaply as bottles of the ordinary construction, and is so formed that the edge of the cap may be pried up, without difficulty.

Having thus described my invention what is claimed as new is:—

1. A bottle of the character described, having a downwardly rounded annular rim at its margin and a flat annular cap-seat on a level with the upper edge of the said rounded rim, and a plurality of cap-engaging lugs projecting upward from the rim, the inner faces of said lugs intersecting the rounded rim exterior to the outer circumference of the cap seat.

2. A bottle of the character described, having a downwardly rounded annular rim at its margin and a flat annular cap-seat on a level with the upper edge of the said rounded rim, and a plurality of cap-engaging lugs projecting upward from the rim, the inner faces of said lugs being exterior to the outer circumference of the cap seat, the inner faces of said lugs being slightly undercut.

3. A bottle of the character described, having a downwardly rounded annular rim portion, and a flat annular cap-seat extending inward from the upper edge of the rounded portion and defining the opening of the mouth of the bottle, in combination with a flat cap resting on said cap-seat and extending on all sides beyond the cap-seat and over the rounded portion of the rim, and means for holding said cap in place.

In testimony whereof I affix my signature in presence of two witnesses.

HARVEY DIKEMAN. [L.S.]
